DESIGN FOR A FONT OF TYPE

Rex Jochim, Oakland, Calif.

Application June 14, 1949, Serial No. 3,280

Term of patent 7 years

(Cl. D64—12)

To all whom it may concern:

Be it known that I, Rex Jochim, a citizen of the United States and a resident of the city of Oakland, county of Alameda, State of California, have invented a new, original, and ornamental Design for a Font of Type, of which the following is a specification, reference being had to the accompanying drawing, forming part thereof.

Figure 3 is a perspective view of the letter S which is typical of the other letters and symbols in the font of type.

I claim:

The ornamental design for a font of type, as shown.

REX JOCHIM.
